UNITED STATES PATENT OFFICE.

VICTOR L. OLSON, OF LEIGH, NEBRASKA.

VACUUM CLEANER.

Application filed June 8, 1927. Serial No. 197,383.

The present invention is directed to improvements in vacuum cleaners.

The primary object of the invention is to provide a device of this character primarily 5 designed for cleaning the upholstery or other parts of an automobile.

Another object of the invention is to provide a device of this kind so constructed that the battery of the automobile is utilized for 10 furnishing current to the motor for actuating the suction fan.

Another object of the invention is to provide a device of this nature which is comparatively light in order that the same can 15 be conveniently handled when in operation.

In the accompanying drawing:

Figure 1 is a longitudinal sectional view through the device.

Figure 2 is a sectional view on line 2—2 of 20 Figure 1.

Figure 3 is a detail sectional view of the cover and dust collector housing, showing the manner in which the dust collector is mounted in the housing.

25 Referring to the drawing, 1 designates a casing of conical formation and having a collar 2 upon its minor end in which is fitted a ball bearing 3, there being a closure cap 4 threaded upon said collar.

30 The major end of the casing is provided with an annular flange 5 to provide a chamber 6, there being a cross bar 7 supported by the flange, the purpose of which will be later explained.

35 An electric motor 8 is located in the casing 1 and is mounted rigidly therein upon brackets 9, as clearly shown in Figure 1 of the drawing, the forward end of the motor shaft 10 being journaled in the cross bar 7 while the 40 rear end thereof is journaled in the bearing 3. To the outer end of the shaft is fixed a fan 11 which occupies the chamber 6 defined by the flange 5.

The flange 5 terminates in an outwardly 45 flared flange 12 which in turn terminates in an annular wall 13 providing a housing 14. A handle 15 is provided and has one end fixed to the flange 5 and its other end fixed to the wall 13.

50 The wall 13 of the housing is formed with an annular flange 16 and upon which seats

the rim of the cover 17, said cover being retained in place by clamps 18 of any suitable construction. The cover carries a centrally located nipple 19 and upon which is fitted 55 a suction hose 20, said hose being equipped with a suction nozzle 20' of any desired form.

A fabric dust collecting sack 21 is located in the housing 14 and has its open end provided with a ring 22 which is held upon the 60 flange 16 by spring arms 23 carried by the cover 17.

The motor has leading therefrom a conductor 24, said conductor being provided with a connector 25 which is designed to 65 be connected to the battery of the automobile in order to energize the motor and rapidly rotate the fan 11. Obviously, when the fan is operating suction will be created in the housing 14 in order to suck dust and dirt collected by the nozzle for lodgment in the dirt collector 21, which being removable, permits the contents thereof to be conveniently emptied when necessary.

The casing 1 is provided with a plurality 75 of perforations 26 for permitting the discharge of the spent air.

Having thus described the invention, 1 claim:

A vacuum cleaner of the class described 80 comprising a conical casing, a bearing mounted in the minor end of the casing, brackets carried by the casing, a motor supported by the brackets, an annular flange carried by the casing and having a cross bar therein, 85 said annular flange defining a chamber, the motor shaft having one end journaled in the bearing and its other end journaled in the cross bar, a fan fixed to the shaft and rotatable in the chamber, a housing supported by 90 the flange and in communication with the chamber, a flange carried by the outer end of the housing, a fabric sack located in the housing and having a ring carried thereby, a cover for the housing, resilient arms carried 95 by the cover for yieldably engaging the ring for maintaining the sack within the housing when the cover is secured in closed position upon the housing.

In testimony whereof I affix my signature.

VICTOR L. OLSON. [L.S.]
